CLAIM

The ornamental design for a housing and support for picture capture apparatus and/or accessory, as shown and described.

DESCRIPTION

FIG. 1 is a front, right-side perspective view of a first embodiment of a housing and support for picture capture apparatus and/or accessory according to my new design; FIG. 2 is a front elevation view thereof;

FIG. 3 is a back elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a front, right-side perspective view of a second embodiment of a housing and support for picture capture apparatus and/or accessory according to my new design;

FIG. 9 is a front elevation view of FIG. 8;

FIG. 10 is a back elevation view of FIG. 8;

FIG. 11 is a left-side elevation view of FIG. 8;

FIG. 12 is a right-side elevation view of FIG. 8;

FIG. 13 is a top plan view of FIG. 8;

FIG. 14 is a bottom plan view of FIG. 8;

FIG. 15 is a front, right-side perspective view of a third embodiment of a housing and support for picture capture apparatus and/or accessory according to my new design;

FIG. 16 is a front elevation view of FIG. 15;

FIG. 17 is a back elevation view of FIG. 15;

FIG. 18 is a left-side elevation view of FIG. 15;

FIG. 19 is a right-side elevation view of FIG. 15;

FIG. 20 is a top plan view of FIG. 15;

FIG. 21 is a bottom plan view of FIG. 15;

FIG. 22 is a front, right-side perspective view of a fourth embodiment of a housing and support for picture capture apparatus and/or accessory according to my new design;

FIG. 23 is a front elevation view of FIG. 22;

FIG. 24 is a back elevation view of FIG. 22;

FIG. 25 is a left-side elevation view of FIG. 22;

FIG. 26 is a right-side elevation view of FIG. 22;

FIG. 27 is a top plan view of FIG. 22; and,

FIG. 28 is a bottom plan view of FIG. 22.

The dash-dot lines adjacent to the shaded areas denote the boundary of the claim and form no part of the claimed

It is certified that error appears in the above-identified patent and that said Letters Patent is hereby corrected as shown below:

In the Specification

In the Description, immediately below the description of FIG. 28, please insert the following sentence:

-- The broken lines in the figures illustrate portions of the HOUSING AND SUPPORT FOR
PICTURE CAPTURE APPARATUS AND/OR ACCESSORY that form no part of the claimed
design. --

Signed and Sealed this
Nineteenth Day of January, 2021

Andrei Iancu
Director of the United States Patent and Trademark Office
